HEATING SYSTEM

Joseph T. Stangl, Dedham, Iowa

Application November 4, 1931, Serial No. 572,892

1 Claim. (Cl. 237—3)

My invention relates to building structures, such as are used as brooders for chickens and so forth.

It is my purpose to provide a hygienic building structure.

More particularly, it is my purpose to provide a building structure, including a building room, having means by which it may be heated, and automatically regulated by a thermostat according to the temperature in the room, and to provide in connection with the parts mentioned a ventilator shaft with a controlling damper therefor actuated in accordance with the temperature of the room by another thermostat, the thermostats being set at slightly different temperatures, so as to maintain constant flow of air from the building room.

It is also my purpose to provide a type of building structure in which the warm air will be evenly and uniformly distributed over the floor, so as to avoid any cool or hot spots.

With these and other objects in view, my invention consists in the construction, arrangement and combination of the various parts of my structure, whereby the objects contemplated are attained, as hereinafter more fully set forth, pointed out in my claim, and illustrated in the accompanying drawing, in which:

Figure 1 is a perspective view of a building embodying my invention.

Figure 2 is a vertical, sectional view taken on the line 2—2 of Figure 1.

Figure 3 is a detail, sectional view taken on the line 3—3 of Figure 2.

Figure 4 is a top or plan view of part of the building room, parts being broken away and parts being shown in section on the line 4—4 of Figure 3.

Figure 5 is a horizontal, sectional view taken on the line 5—5 of Figure 2, parts being broken away.

Figure 6 is a detail, sectional view taken on the line 6—6 of Figure 1; and Figure 7 is an enlarged view on the section line 3—3 of Figure 2.

I have illustrated my invention as it is used with a building, having the floor 10, the end walls 11 and 13 and the roof 15, which is formed in the shape of a part of a cylinder. The ends 50 of the house may be provided with windows 16. Suitable doors 17 may be provided.

I preferably place a brooder stove 18 approximately at the center of the building, providing it with a stack 19 extending through the top of the building. The stove is of any ordinary type

controlled by a thermostat 20, which is at the lower part of the stove, projecting away perhaps ten inches.

At the end of the room opposite the doors midway between the sides is a ventilating shaft 21, preferably composed of sheet metal, and projecting from the top of the building. The imperforate part of this ventilating shaft terminates about sixteen inches above the floor and the lower part is formed of screen wire or the like 22. This height is selected to take excessive heat away above the chicks and to prevent an over-warm draft on the chicks.

At the lower end of the imperforate part of the ventilating shaft 21, the flow of air therethrough is controlled by a damper 23, having a stem or the like journaled in the walls of the shaft.

Mounted on a suitable bracket 25 is an adjustable thermostat 26, which actuates a rod 27 pivoted as at 28. This rod is pivoted to a link 29, which is in turn pivotally connected with a crank 30 on the stem 24, but, of course any suitable means may be provided for operating the damper from the thermostat.

In actual use, the two thermostats are set about two degrees apart.

I find that with this arrangement, I can secure desirable ventilation and ample fresh air and heat control, thus preventing overheating the chicks.

Little chicks are very sensitive and it is highly desirable that the temperature control should be accurate. I have found that where an ordinary brooder stove is used, it is hard to avoid considerable variations in the temperature on the floor, especially where rather sudden changes take place in the outside temperature.

The heat continues to increase after the thermostat has operated and likewise the stove fails to heat up instantly after the thermostat has operated to turn on the heat. It is also hard to get an even temperature on the floor in most buildings because of their shape.

I find that by using the substantially semi-cylindrical building, I am able to maintain the warm air more evenly and uniformly distributed over the floor than with other types of buildings.

Another great difficulty experienced in raising chicks is that of maintaining a constant supply of fresh air and oxygen in the brooder room, while at the same time properly controlling the temperature in the room at a given degree.

Where some sort of damper or the like is employed with apparatus of the kinds heretofore

used, there are periods for instance when the temperature outside remains the same for considerable lengths of time, when there is almost no fresh air supplied to the room. Where my device is employed, I find it easier to maintain an even temperature and also to maintain a constant flow of air through the brooder room. Owing to the fact that the two thermostats are set for different temperatures, there is a constant changing of the damper position and of the heat control. When the room gets too hot, the stove thermostat shuts off the heat and the ventilator opens the damper (assuming the ventilator thermostat to be set two degrees below the stove thermostat). The air continues to pass out of the ventilator so that the proper temperature is reached in a very short time. The room does not continue to heat up as long as where some other system might be used.

On the other hand, when the outside temperature cools off suddenly, the ventilator thermostat at once closes the damper, so that the flow of air into the building and out of it is reduced, and if the temperature in the room continues to lower, then the stove thermostat operates to give greater heat. If the temperature remains about the same for a considerable length of time, then the arrangement of the thermostats at different temperatures will insure constant flow of air, because the damper will not be fully closed when the stove is heating to the proper temperature.

The difference in the setting of the thermostats will tend to cause either the stove or the ventilator to vary the temperature in the room from the normal desired, but this tendency is so slight that the ultimate result is to maintain an evener temperature than would otherwise be possible.

The result is contributed to by the fact that the air comes in at a variety of places.

I find that in a house of this kind, the air comes in at the ends where the joints are formed between the sides and the tops of the end walls with the roof and at the joints between the end walls and the floor. I find that, however well the buildings may be constructed, there is an ample supply of fresh air supplied at the joints and this affords an evener supply of air around the building, than is possible where window or door or intake shaft is used for supplying fresh air.

I preferably provide a fresh air inlet duct 40, extending through the wall below the ventilating shaft 21, and extending to a point below the pipe 19 and communicating with an upright pipe 41, which surrounds the pipe 19 so that the air brought in through the duct 40 will be warmed before being discharged into the room. Flow of air through the duct 40 is controlled by a sliding damper 42 which is operatively connected by means 43 with the damper 23, so that these dampers open and close together.

There is thus afforded a truly hygienic brooder in which the temperature is properly maintained and a constant and ample supply of fresh and heated air is provided.

I have provided an exceptional joint construction between the roof and the front wall at the ends of the brooder house, by which I am enabled

to provide for the intake of fresh air through a number of small passages, which are separated around the curve of the roof, so that the air will come in at a number of openings in a small quantity at each opening.

In Figure 6, I have illustrated a part of this construction. I provide a curved rafter 34a, which fits snugly under the roof 35, which is covered by the prepared roofing 36. Spaced from the rafter 34a a short distance is another curved rafter 39 to which the end wall 37 is fastened. Some air enters between the upper edges of the rafter 39 and wall 30, and the roof. The roof 35 projects over the front wall 37 a trifle, for instance about an eighth of an inch. A curved cornice board 38 is fastened to the projecting end of the roof 35 and thus affords an air intake space between it and the wall 37. The wall 37 and the rafters 39 and 34a are preferably fastened together by bolts 35a. The heads 36a of these bolts serve as spacers for the cornice boards. On the bolts 35a between the rafters 34a and 39 are spaced washers 37a.

This construction is not intended for supplying sufficient ventilation in hot weather when the windows or doors can be opened, but in cold weather it provides for an ample supply of fresh air evenly distributed around the roof at both ends of the house. With such an arrangement, there is no danger of the creation of any strong drafts to affect the chicks and enables me to secure the result which I have heretofore explained of securing uniform temperature of the air for the chicks over the entire floor.

It will, of course, be understood that the material employed in building the house may be such as is available and desirable. However, I preferably use sheet metal for the ventilator shaft 21, because it is such a good conductor of heat, and I find that the use of the sheet metal tends to create a draft upwardly which contributes to the maintenance of continuous ventilation.

Changes may be made in the details of the construction and arrangement of the parts of my improved sanitary building structure without departing from the essential features and purposes of my invention, and it is my intention to cover by my claims any modified forms of structure or use of mechanical equivalents, which may be reasonably included within their scope.

I claim as my invention:

In a structure of the kind described, a room, a ventilator shaft therein for taking air from a point near but above the floor of the room and discharging it from the room, a heater in the room spaced from said shaft, a pipe surrounding the heater and discharging above it, an intake air duct extending from below the shaft to the pipe, dampers in the shaft and the duct, a thermostat in the room, operatively connected with the dampers for opening both at the same time, when the room temperature falls below a predetermined point, and a thermostat in the room for controlling the heater set for a slightly different temperature from the setting of the first thermostat.

JOSEPH T. STANGL.
